UNITED STATES PATENT OFFICE

LOUIS V. JOHNSON, OF BROOKLYN, NEW YORK

POCKET PROTECTOR

Application filed August 19, 1930. Serial No. 476,412.

This invention relates to protectors for pockets and has for an object to provide an improved construction which may be used in any pocket although particularly adapted for hip pockets on pants, the structure being such that the usual appearance of the pocket is retained and yet means is provided which will prevent accidental or unauthorized removal of the contents of the pocket.

Another object of the invention is to provide a pocket structure which presents a protecting member positioned to leave the pocket normally open while covering the pocket-book or other articles in the pocket in such a way that an unauthorized person cannot readily remove the pocket-book or other contents.

A further object of the invention more specifically is to provide a protector for pockets wherein a flap is arranged exteriorly of the pocket and preferably merging into a depending sheet adapted to extend to the bottom of the pocket and to cover the pocket-book or other articles in the pocket so that when a hand is placed in the pocket it will not come in contact with the pocket-book or other contents of the pocket.

In the accompanying drawings—

Figure 1 is a rear view of a figure wearing a pair of pants with the rear or hip pocket constructed according to the present invention;

Figure 2 is an enlarged fragmentary view of the pocket showing the parts disclosed in Figure 1, certain of the parts being broken away for better illustrating the construction;

Figure 3 is a view similar to Figure 2 but showing the protecting sheet arranged exteriorly;

Figure 4 is an enlarged fragmentary sectional view through Figure 1 on the line 4—4;

Figure 5 is an enlarged fragmentary sectional view through Figure 2 on the line 45 5—5;

Figure 6 is an enlarged fragmentary sectional view through Figure 3 on the line 6—6.

Referring to the accompanying drawings by numerals, 1 indicates the pocket which may be of any desired structure, and 2 a flap

secured to the outer edge of the pocket and positioned to appear to close the opening 3. The flap 2 is provided with the usual button-hole 4 coacting with the usual button 5 secured to the cloth 6 of the trousers. If the flap 2 is unfastened from the button 5 access to the pocket cannot be secured and consequently a thief or unauthorized person attempting to place a hand in the pocket by forcing same upwardly beneath the flap 2 will be disappointed as the hand will merely strike against the seam 7 which secures the various parts to the trousers 6.

A reinforcing member 8 is secured in place by stitching 7, and in addition a sheet 9 is secured in place by stitching 7, said sheet being preferably doubled and arranged so that it merges into the flap 2 as an integral structure.

It will be noted that the protecting sheet 9 is entirely independent of the pocket 1 except for its connection by the stitching 7. This will be evident from Figures 3 and 6 where the sheet is shown positioned exteriorly of the pocket. In use the protecting sheet 9 is never in this position but is always in the position shown in Figures 2 and 4. When placing an article such as a pocket-book 10 in the pocket it may be necessary to remove the sheet 9 to a position shown in Figure 3, after which the pocket-book or other article may be inserted and then the protecting sheet is inserted to the position shown in Figure 4. It will be noted that the protecting sheet 9 extends to a point adjacent the bottom of the pocket 1 so that when an authorized or unauthorized hand is placed through the opening 3 it will not come in contact with the contents of the pocket, and such contents cannot be removed until the sheet 9 has first been removed. This will prevent pickpockets or other unlawful persons from removing articles from a pocket.

When the pocket is completed it will appear as shown in Figure 1 and will thereby give the appearance of the usual pocket having a flap covering the opening. However, as shown in Figure 4, the flap 2 does not cover the opening and consequently a hand may be readily inserted at any time.

The protecting member or sheet 9 is adapted however to fully cover any article in the pocket and to prevent its removal until the protecting sheet has been first removed. In 5 this way an unauthorized person cannot remove a pocket-book or other article from the pocket without the owner of the pocket becoming aware of his actions.

What I claim is:

- 10 A safety pocket including a pocket structure having an opening at the top, means for securing the pocket structure to a garment, a sheet having a portion looped over the outer part of the pocket structure and 15 garment to form a flap externally of the pocket structure, and a loose portion extending into the pocket to a point near the bottom to present a protecting sheet, said sheet being coextensive with the interior of the pocket 20 and adapted to cover an article carried by the pocket.

Signed at Brooklyn, in the county of Kings and State of New York, this 18th day of August, 1930.

25 LOUIS V. JOHNSON.
